UNITED STATES PATENT OFFICE.

WILLIAM W. WOOD, OF RAYMOND, WASHINGTON.

FOLDING BERRY-BOX.

982,919.

Specification of Letters Patent. Patented Jan. 31, 1911.

Application filed October 27, 1910. Serial No. 589,443.

To all whom it may concern:

Be it known that I, WILLIAM W. Wood, a citizen of the United States, residing at Raymond, in Pacific county, State of Washington, have invented a certain new and useful Folding Berry-Box, of which the following is a specification.

This invention relates to boxes for the shipping and sale of small berries and is 10 more particularly an improvement in the folding berry box patented by me on June 28th, 1910, under Number 962,607, and has for its object to make a box which will be cheaper to make and more easily assembled 15 at the factory, and which will be very quickly opened for use. I attain these and other objects by the devices and arrangements illustrated in the accompanying drawing, in which—

20 Figure 1 is a plan of the strip of veneer cut and scored to form the four sides of the box; Fig. 2 is a vertical section of the box showing the bottom thereof being placed into position for use; Fig. 3 is a similar view 25 showing the bottom in position for use; and Figs. 4 and 5 are front and rear views, respectively, of the box with the bottom in a position similar to that shown in Fig. 2.

Similar numerals of reference refer to 30 similar parts throughout the several views.

The four sides of this improved box are formed of a single piece of wood veneer, or other thin material, suitably scored in four substantially equidistant lines so as to divide it into five equal parts. The part 1 at one end thereof is provided with an indent 35 8 in the center of its lower edge, and the part 5 at the other end of the strip, is cut or slotted at 7 near its lower edge, said slot 7

40 extending from the end of the strip to the score and being parallel with the lower edge. The strip 6, which is separated from the part 5 by the slot 7, is secured to the next part 4 at the score. The bottom 9 is formed of a 45 similar strip of veneer, having two scores across it near its ends whereby it is provided with a part 10 at one end by means of which it is secured to the side of the box, and with a part 11 which is adapted to pass through 50 the slot 7 and between the strip 6 and the

side 1 to bring the bottom 9 level and resting on the edge of the strip 6. The box is formed by bending the strip along the four scores and placing the side 1 outside of the side 5, and then securing the side 1 to the 55 piece 6 at its two ends by means of the two staples 12 and 13 near the lower edge of the side 1 and securing the upper corner of said side 1 by a staple 14 to the side 5 near the score between the sides 4 and 5. The bottom 60 is secured to the side 3 by the staples 15 and 16 which pass through the side 3 near the lower edge thereof and through the part 10 of the bottom. The staples 12 and 13 are preferably placed at opposite angles 65 so as to be out of the way of the flap 11 of the bottom, said flap 11 also having its corners suitably cut off for the same purpose.

My improved box is folded by lifting the 70 bottom 9 until it lies flat against the side 3 to which it is attached, and then folding the opposite side formed of the parts 1 and 5 against one of the adjacent sides 2 or 4 thus making the box pass from a rectangle 75 to a flat parallelogram. It is unfolded for use by drawing the side, formed by the sides 1 and 5, outward until the box is rectangular and then bringing the bottom down into the box and simultaneously with one finger 80 pressing the strip 6 inward through the indent 8 thus separating the part 1 from the part 6 and allowing the part 11 of the bottom to easily pass through the slot 7 and between the parts 6 and 1. Since the part 85 6 is secured to the part 1 at both ends it is very strong.

Having described my invention, what I claim is:

In a folding berry box, the combination 90 of a strip having four transverse scores therein dividing it into five equal parts and adapted to be folded with its two end parts lying one outside of the other, the outer of said parts having an indent cut in the center 95 of its lower edge, and the inner of said parts having a slot cut from its end to the score, parallel with and near the lower edge thereof thus forming a supporting strip; means whereby said supporting strip is secured to 100

said outer indented part at its ends but is separable therefrom between said securing means; and a bottom strip secured at one end to the lower edge of the middle section 5 of said box strip and having its other end bent downward and its corners cut whereby said bent end is adapted to pass through the

slot and between said supporting strip and the outer indented part.

WILLIAM W. WOOD.
